The ornamental design for an apparatus for projecting video images, as shown and described.

DESCRIPTION

FIG. 1 is a front left perspective view of the apparatus for projecting video images showing my new design;

FIG. 2 is a rear right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a perspective view thereof with the lens turned upright.
